UNITED STATES PATENT OFFICE.

JOSEPH E. CLARK AND STEPHEN C. TAFT, OF FRANKLIN, MASSACHUSETTS

MACHINE FOR SCOURING WOOL.

SPECIFICATION forming part of Letters Patent No. 424,405, dated March 25, 1890.

Application filed February 4, 1889. Serial No. 298,616. (No model.)

To all whom it may concern:

Be it known that we, JOSEPH E. CLARK and STEPHEN C. TAFT, citizens of the United States, residing at Franklin, in the county of Norfolk 5 and State of Massachusetts, have invented certain Improvements in Machines for Scouring Wool, of which the following is a full, clear, and exact description, reference being had to the accompanying drawings, making part of this specification, in which—

Figure 1 is a plan of a machine for scouring wool constructed in accordance with our invention. Fig. 2 is a vertical section of the same on the line xx of Fig. 1. Fig. 3 is a plan 15 of the machine, the wringing - roller being taken off and the endless apron being removed to show the perforated pipes at the bottom of the tank. Fig. 4 is a sectional detail, enlarged, showing one of the sprocket or chain wheels 20 and a portion of one of the apron - driving chains with which the sprocket-wheel engages. Fig. 5 is a detail, enlarged, showing the ratchet and pawl at the end of one of the apron-rollers. Fig. 6 is a sectional detail, enlarged, illustrating the manner in which the perforated 25 air-pipes are sunk flush with the bottom of the tank.

Our invention relates to certain improvements in machines for scouring wool, and has for its object to keep the scouring-liquor in the tank in a constant state of agitation or ebullition without any increase of heat, as would occur if the movement of the liquor were produced by the introduction of steam, 35 which could not be successfully employed for this purpose, as it would necessarily produce a degree of heat sufficient to injure the wool.

To this end our invention consists in an apparatus in which air under pressure is introduced through a suitable perforated pipe or pipes into the bottom of the tank which contains the scouring-liquor and the wool, whereby the liquor is kept in a constant state of motion or ebullition without any increase of heat, this movement or agitation of the liquor causing the fibers of the wool to be quickly loosened and opened up and exposed in every part to the action of the said liquor, whereby the work of scouring is performed in a perfect, 45 rapid, and satisfactory manner.

Our invention also consists in the combina-

tion, with the scouring-tank provided with a pipe or pipes adapted to convey air under pressure and discharge it beneath the liquor in said tank to produce an agitation or ebullition of the same, of suitable water and steam pipes connected with said air pipe or pipes and provided with suitable valves, whereby water can be discharged through the air pipe or pipes into the tank to fill the same, and steam also admitted through the same pipe or pipes to heat the liquid to the desired temperature, as hereinafter set forth; and our invention also consists in the combination, with the tank, of a slack endless apron running over suitable supporting rollers or shafts and driven by supporting-chains running over sprocket-wheels or in other suitable manner, said apron passing over the top of the tank and around underneath the bottom of the same, and being adapted to be lowered to the bottom of the tank before the wool is placed therein and afterward elevated by taking up the slack between its points of support to raise the scoured wool out of the liquor and allow it to drain, the subsequent onward movement of the apron causing the wool thereon to pass under a wringing or squeezing roller and thence out of the machine, as hereinafter more fully set forth; and our invention also consists in certain novel combinations of parts and details of construction, as hereinafter set forth and specifically claimed.

In the drawings, the tub or tank of a wool-scouring machine, which rests on the floor or other suitable support, and may be of any well-known or desired shape. Transversely across this tank A extend a series of horizontal pipes b, which are sunk or embedded to the extent of their diameter in grooves c, 85 formed in the bottom of the tank, as seen in Figs. 2 and 6, whereby they are protected and prevented from projecting up above the bottom of the tank, which is thus left free from obstructions and the labor of cleaning it 90 greatly facilitated. The pipes b are provided with perforations or apertures on the upper side and are connected outside the tank A with a main supply-pipe B, which is provided with a valve d, and is connected with a blower 95 or air-compressor, (not shown,) whereby air under pressure is forced into the pipes b and 100

discharged through the perforations of the same under and into the scouring-liquor contained in the tank A, whereby a violent agitation or ebullition of the same is produced without any increase of heat, the agitation of the liquor causing the wool therein to be kept in constant motion, whereby its fibers are rapidly opened up, so as to be exposed in every part to the action of the scouring-liquor, causing the grease, wax, or sebaceous matter to be quickly loosened and removed, as desired.

C D are steam and water pipes, which are connected with the main pipe B and are provided with valves e f for regulating or shutting off the supply of water or steam, as may be required, and in this manner water and steam may be discharged into the tank A through the same perforated pipes b as are employed for discharging the compressed air, thus simplifying the construction of the apparatus and affording a ready and convenient means of filling the tank with water and heating it by steam to the proper temperature for scouring the wool. Each of the perforated pipes b opposite to the end where it is connected with the main pipe B is provided with a blow-off cock g, for the purpose of keeping the pipes b clean and free from obstructions. G is a slack endless apron composed of narrow metallic strips or slats h, Figs. 1 and 4, which are secured at their opposite ends and at the center to machine-chains i, which pass over and engage with sprocket or chain wheels k, secured to rollers H I at the center and at their opposite ends, as seen in Fig. 3, these rollers being supported in suitable bearings at the opposite ends of the tank A. The diameter of the chain-wheels should be slightly less than that of the rollers H I, to which they are secured, in order that the apron-slats h may rest upon the surfaces of said rollers as they pass thereover. The chains i, with the apron G secured thereto, are driven by the roller H, the shaft of which is provided with a gear l, which meshes with a pinion n on a shaft p, carrying fast and loose pulleys, over which passes a driving-belt q, which is shifted to stop or start the roller H by a shipper-lever r, with which is connected a bar s, provided with a handle t within reach of the operator. The apron G extends over the top of the tank A and is of such length as to run with considerable slack under the bottom of the machine, passing through slots or apertures u in the floor on which the machine rests and under the floor-timbers, as seen in Fig. 2, the width of the apron being slightly less than that of the interior of the tank to permit it to be dropped down to the bottom of the same into the position seen in Fig. 2 before the introduction of the wool, the slack portion of the apron beneath the machine being sufficient to permit this to be done. The roller I is provided with a crank-handle v, by means of which the roller can be turned by hand and its motion controlled as may be

found desirable, and to the shaft of this roller is secured a ratchet-wheel a', having square teeth, as seen in Fig. 5, with which engages a pawl b', by means of which the roller can be locked and prevented from rotating in either direction.

Immediately above the apron-driving roller H, and arranged to operate in connection therewith, is a heavy squeezing or wringing roller L, the journals of which rest in slots 10 in inclined uprights c', whereby the roller L is permitted to rise and fall to accommodate itself to the thickness or quantity of wool carried beneath it by the movement of the apron G, which is raised out of the tank by tightening its slack between the rollers H I, which is effected by arresting the motion of the roller I by dropping the pawl b' between the teeth of the ratchet-wheel a' and continuing the motion of the driving-roller H, whereby the apron, with the wool thereon, is drawn out above the level of the scouring-liquor in the tank, the wool, after draining through the spaces between the slats h, being carried by the subsequent onward movement of the apron between the roller H and squeezing-roller L, and thence out of the machine into a receptacle placed to receive it.

The operation is as follows: The endless apron G having been lowered to or nearly to the bottom of the tank A, as seen in Fig. 2, the valve f of the water-pipe D is opened, when cold water will be discharged into the tank through the perforated pipes b. As soon as the tank has been filled to the desired height, the water is shut off and the steam-valve e opened, when steam will be discharged through the perforations of the pipes b into the cold water previously introduced into the tank, which is in this manner heated to the desired degree. A suitable quantity of the ordinary alkaline liquor used by wool-scourers is next mixed with the water in the tank, after which the valve d in the main supply-pipe B is opened to admit compressed air, which is then discharged through the perforations of the pipes b beneath and into the liquor contained in said tank, the compressed air as it rises through the liquor producing a violent agitation or ebullition of the same. The wool is now thrown into the bubbling liquor, and as it is moved in all directions thereby its fibers are loosened and quickly opened up and exposed in every part to the action of the scouring-liquor, whereby the dirt, grease, and sebaceous matter are removed and the scouring operation performed in a rapid and superior manner. After the wool has been sufficiently scoured the roller I is locked and prevented from rotating by dropping the pawl b' between the teeth of the ratchet-wheel a', when the roller H is set in motion by operating the shipper-lever r. The roller H now revolves slowly and raises the apron G, with the wool thereon, out of the liquor into the position shown by dotted lines in Fig. 2, the liquor raised with the wool

draining through the spaces between the slats of the apron. The motion of the roller H is then arrested by operating the shipper-lever *r*, after which the wool is allowed to drain in this position for a few moments, when the roller H is again set in motion and the opposite roller I released and held under control by the hand of the operator, which is placed upon the crank-handle *v*, so as to prevent the apron from being again carried down into the tank by the weight of the wool thereon. The driving-roller H as it revolves now carries with it the apron G and the scoured wool thereon in the direction of the arrow, Fig. 2, causing the 5 wool to pass under the wringing-roller L, which squeezes out nearly all the liquor, which drains back into the tank while the wool is carried forward by the apron beyond the wringing-roller, when it falls into a suitable receptacle placed to receive it. The centers of the rollers H L are not in the same vertical plane, that of the roller L being slightly inside, which enables the liquor 10 squeezed out of the wool to more readily fall back into the tank, the weight of the roller L, as it moves up and down within the slots 15, being sufficient to squeeze the water out of the wool without the assistance of springs or any other auxiliary device. The air introduced through the perforated pipes *b* may be at a pressure of from five pounds to the square inch upward. It is obvious that if it should be desired to raise the temperature of the liquor in the tank while the operation of 20 scouring is in progress that the steam-valve *e* may be opened and steam admitted simultaneously with the compressed air, and that water may also be admitted through the valve *f* simultaneously with steam and air, if desired, and when the air-valve is opened to admit the compressed air the pressure of the steam and water being admitted therewith should never exceed that of the air. When, 25 however, the air-valve is closed, steam or water at any desired pressure may be admitted.

The compressed air may be introduced cold, or may be previously heated, if desired.

The great advantage of agitating or producing a movement of the liquor in the scouring-tank by means of compressed air instead of by means of steam is that with compressed air the required agitation or ebullition can be produced without increasing the heat to such a degree as to injure the wool, whereas if the agitation of the liquor should be caused by the introduction of steam the heat would necessarily be so great as to injure the wool.

By the employment of a slack endless apron arranged, as described, to extend around under the bottom of the machine, and operated as described, the scoured wool is raised out of the liquor, delivered to the wringing or squeezing roller, and carried out of the apparatus without the use of forks or rakes, which are objectionable on account of their liability to tear and break the fibers of the wool. Furthermore, the operation is performed by the apron in very

much less time than it can be done by manual labor with a fork, while the agitation of the wool and the loosening and opening up of its fibers by the action of the compressed air upon the liquor also avoids the necessity of employing rakes or other mechanism to stir the wool about in the liquor, as heretofore, thus also avoiding the breaking and tearing of the fibers from this cause.

It will be obvious that a pipe or pipes provided with perforations or apertures and adapted to convey compressed air and discharge it into and beneath the scouring-liquor, as above described, may be applied to a wool-scouring tub or tank of angular, circular, or other desired shape, and that the disposition and arrangement of the air pipe or pipes at the bottom of the tank may be varied as desired without departing from the spirit of our invention; and, moreover, if desired, the endless apron may be employed in connection with the compressed-air pipe or pipes, or dispensed with if it should be desired to merely retain the advantages incident to the use of the said air pipe or pipes.

We do not confine ourselves to the employment of steam and water pipes in connection with the compressed-air pipe or pipes, as either the steam or water pipes, or both, may be dispensed with and the water heated and introduced into the tank in any other suitable manner.

What we claim as our invention, and desire to secure by Letters Patent, is—

1. A scouring-tank provided at its bottom with perforated pipes that discharge into the tank beneath the liquor therein, said pipes being connected to an air-pipe having valved steam and water pipes connected thereto, whereby air, steam, and water, either separately or together, can be discharged into the tank through the same discharge-pipes, substantially as described.

2. In a wool-scouring machine, the combination, with the tank A, of the slack endless apron G, mounted on suitable shafts or rollers and extending over the top of the tank and outside around the bottom of the same, mechanism, substantially as described, for actuating the apron, and a device for arresting and controlling the movement of the same at one end of the tank, whereby the slack portion within the tank, with the wool thereon, is raised up out of the liquor, and the wool, after draining, carried by the subsequent movement of the apron beneath a squeezing or wringing roller, substantially as set forth.

3. In a wool-scouring machine, the combination, with the scouring-tank, of the slack endless apron G, composed of slats and mounted on supporting-rollers H I, the supporting-chains *i*, secured to said endless apron and passing over sprocket or chain wheels on the rollers H I, one of said rollers being driven by suitable motive power and the opposite roller being provided with a hand-crank *v*, and a ratchet-and-pawl mechanism, whereby

the movement of said apron is arrested at one end of the tank to allow it to be raised out of the liquor in the same by the movement of the driving-roller, and the movement of said apron controlled while the wool is being carried thereby beneath the squeezing or wringing roller, all operating substantially in the manner and for the purpose set forth.

Witness our hands this 1st day of February, A. D. 1889.

JOSEPH E. CLARK.
STEPHEN C. TAFT.

In presence of—
P. E. TESCHEMACHER,
HARRY W. AIKEN.
